R. HITCHCOCK

PAPER FOLDING MACHINE

Filed Aug. 13, 1923

FIG. 2.

FIG. 1.

Inventor:

REUBEN HITCHCOCK,

Albert C. Gurnea
Attorney.

Patented Aug. 19, 1924.

1,505,920

UNITED STATES PATENT OFFICE.

REUBEN HITCHCOCK, OF CLEVELAND, OHIO, ASSIGNEE TO THE CLEVELAND FOLDING MACHINE COMPANY, OF CLEVELAND, OHIO, A CORPORATION OF OHIO.

PAPER-FOLDING MACHINE.

Application filed August 13, 1923. Serial No. 657,018.

To all whom it may concern:

Be it known that I, REUBEN HITCHCOCK, a citizen of the United States of America, residing at Cleveland, in the county of 5 Cuyahoga and State of Ohio, have invented certain new and useful Improvements in Paper-Folding Machines, of which the following is a specification.

My invention relates to improvements in 10 paper folding machines and more particularly to the provision in such machines of a guide and a support for folding plate members while the same are out of service; the object of my invention being the provision 15 of means for storing and for readily placing in use the folding plate members.

Owing to the compact arrangement of parts necessary in a paper folding machine, hitherto it has been difficult to insert and 20 move the folding plate members, particularly as said members must be closely spaced and adjusted with respect to the train or set of folding rolls. In order to do this the operator was required to creep beneath the 25 machine and support the weight of the folding plate member in awkward positions until properly placed or removed from the operative position thereof.

Accordingly I have provided suitable ways 30 or guides wherein the folding plate member may be advanced to or retracted from its position with respect to the folding rolls. Associated therewith is a support interiorly 35 of the machine frame which serves as a magazine for the folding plate member when not in use.

The structural features and advantages of the embodiment of my invention may be more readily explained in connection 40 with the accompanying drawings thereof, wherein:

Figure 1 is a fragmentary view principally in vertical section illustrating the paper folding machine equipped with my 45 improvements, and:

Fig. 2 is an end view thereof intermediately broken away.

Throughout the several figures of the drawings I have employed the same character of reference to indicate similar parts.

Referring initially to Fig. 1, the frame *a* of the paper folding machine is provided with the sheet delivery table *b* intimately associated with the train or set of folding rolls *c*. Said rolls are equipped with the re-

movable folding plate *d*, shown in operative position, and the deflector *d'* shown in dotted line position on the level above said folding plate.

Laterally positioned at the upper portion 60 of the machine frame are the angle iron slides *e* terminating in the hooks *e'* and provided with a switch or sub support *e''* serving the lower level of the folding rolls.

The deflector *d'* is shown supported by 65 the hooks *e'* in the magazine ready for adjustment with respect to the folding rolls. This is very readily accomplished because the operator may slide the lateral lugs or members *d''* along the lateral supports 70 which carry much of its weight, and into the dotted line position above, or the parallel position immediately below said dotted lines, if the folding plate *d* has been removed; the switch *e''* serving to permit the transfer 75 or interchange of these appliances, which I may term generically as folding plate members. Similarly, the folding plate *d* may be supported alternatively in the magazine when desired. 80

When equipped with my improvement it is a matter of only a few moments delay and effort to shift the folding plate members into any desired position since they are supported and guided throughout their 85 movement into and out of place. Moreover it is unnecessary to remove a folding plate member from the frame structure and store it elsewhere, since the magazine affords a most convenient receptacle therefor. 90

Having now described the preferred embodiment of my invention, I claim as new and desire to secure by Letters Patent, together with such modifications thereof as may be the result of ordinary skill in the 95 art, the following:

1. The combination with a paper folding machine having folding rolls and a coacting folding plate member, of lateral guides and terminal supports provided on the frame of 100 the machine adapted to aid the insertion and removal of the folding plate member into and from its operative position, substantially as set forth.

2. The combination with a paper folding 105 machine having folding rolls and a plurality of coacting folding plate members adapted to be removably associated with said rolls, of lateral supports provided upon the frame of said machine along which the folding 110

plate members may be advanced and retracted to and from each of their operative positions with relation to said folding plates, substantially as set forth.

5 3. The combination with a paper folding machine having folding rolls and a plurality of coacting folding plate members adapted to be removably associated with said rolls, of

lateral supports provided upon the frame of said machine affording branches or switches 10 to each operative position for said folding plate members and a magazine for storage, substantially as set forth.

In testimony whereof I do now affix my signature.

REUBEN HITCHCOCK.
